[57] **ABSTRACT**

The present invention is concerned with compounds of Formula I:

I

wherein R₁ is heteroaryl and R₂ is alkyl, aryl, or heteroaryl.

Compounds of this invention exhibit central nervous system depressant properties.

4 Claims, No Drawings

N QUINOLINE 5 AMINOOXAZOLES

This application is a divisional application of my copending application U.S. Ser. No. 843,762, filed July 22, 1969 now U.S. Pat. No. 3,624,097 granted Nov. 30, 1971.

The present invention relates to N-heteroaryl 5-aminooxazoles having the following structural formula:

10

15

wherein R₁ is heteroaryl and R₂ is lower alkyl, aryl, aralkyl, or heteroaryl.

In the above definitions for R₁ and R₂, the term "heteroaryl" encompasses the monocyclic and bicyclic hetero aromatic compounds having at least one hetero atom in the ring which may be either nitrogen, oxygen or sulfur. Representative heteroaryl radicals falling within this definition are, for example, pyridine, quinoline, pyrrole, indole, thiophene, benzimidazole, tetrazole, pyrimidine and the like. The term "aryl" denotes an aromatic radical, preferably of six to 10 carbon atoms, such as for example, phenyl, tolyl and the like. The term "aralkyl" encompasses lower alkyl groups in which an aryl group as defined above is substituted for a hydrogen atom, such as for example, benzyl, phenethyl and the like. The term "lower alkyl" as used herein includes lower aliphatic hydrocarbons having one to five carbon atoms arranged in a straight carbon chain.

The compounds of this invention are useful in cases where a reduction in skeletal muscle spasm is indicated. For example, at a dose of 200 mg/kg intraperitoneally in laboratory animals, such as rats, the compounds of this invention produce a reduction in body tone lasting for 24 hours. Simultaneously, the motor activity and temperature are also decreased for a period of about 3 to 6 hours. Generally speaking, a dose range from 100 to 500 mg/kg is recommended to produce the desired reduction in motor activity. This dosage regimen may, of course, be varied according to body weight, sex, age, species of the mammal being treated as well as the severity of the condition being treated, by methods well known to the healing art.

In order to use these compounds, they are formulated with such standard pharmaceutical carriers, such as lactose, mannitol, dicalcium phosphate into dosage forms such as tablets, capsules and the like. They can also be combined with parenterally acceptable vehicles such as sesame oil, arachis oil and the like to form dosage forms suitable for parenteral injection.

According to the present invention, compounds of Type I are prepared by acylation of heteroaryl amines of Type III with azlactones of Type II followed by cyclodehydration of the intermediate compounds of type IV. The foregoing reaction is illustrated by the following schematic diagram:

II

III

65

IV

in which R₁ and R₂ are as previously defined.

Starting compounds III are readily available from commercial sources, for example, Aldrich Chemical Co. Azlactones of type II were prepared by the procedure described in *Organic Syntheses*, Vol. 47, p. 101 (John Wiley & Sons, Inc., New York, New York, 1967).

The following examples are included in order further to illustrate the invention.

EXAMPLE 1

20 N-[(2-Pyridylcarbamoyl)methyl]benzamide

A solution of 1 g. 2-aminopyridine and 1.75 g. of 2-phenyl-5-oxazolone in 50 ml. of THF is refluxed for 9 hrs. Concentration to half the original volume and chilling on an ice bath produces crystals, which are recrystallized from ethyl acetate. M.P. 172°-174°; Yield: 0.6 g. (21 percent).

Anal. Calcd. for C₁₄H₁₃N₃O₂: C, 65.87; H, 5.13; N, 16.46.

Found: C, 65.85; H, 5.07; N, 16.65.

EXAMPLE 2

40 N-[(2-Quinolylcarbamoyl)methyl]benzamide

Is prepared in the same manner as N-[(2-pyridyl carbamoyl) methyl]benzamide using 1 g. 2-aminoquinoline, 1.1 g. 2-phenyl-5-oxazolone and THF. The product is recrystallized from absolute EtOH. M.P. 218°-219°; yield: 1.7 g. (81 percent).

Anal. Calcd. for C₁₈H₁₅N₃O₂: C, 70.80; H, 4.95; N, 13.76.

Found: C, 70.98; H, 5.00; N, 13.95.

EXAMPLE 3

2-[(Phenyl-5-oxazolyl)amino]pyridine

5 g. N-[(2-pyridyl carbamoyl)methyl]benzamide is added to 100 g. of PPE and stirred for 45 hrs. The solution is poured onto 300 ml. of ice and water with stirring and basified with ammonium hydroxide. The

precipitate is filtered, washed with water and is recrystallized from abs. ethanol. M.P. 169°-170°; yield: 1.5 g. (32 percent).

Anal. Calcd. for $C_{14}H_{11}N_3O$: C, 70.87; H, 4.67; N, 17.71.

Found: C, 70.98; H, 4.71; N, 17.80.

EXAMPLE 4

10

190°-192°; yield: 2.7 g. (72 percent).

Anal. Calcd. for $C_{18}H_{13}N_3O$: C, 75.24; H, 4.56; N, 14.63.

Found: C, 75.15; H, 4.56; N, 14.60.

5

I claim:

1. A compound of the formula:

1

15 wherein R_1 is quinolyl and R_2 is lower alkyl, or phenol.

2. A compound according to claim 1 which is 2-[(phenyl-5-oxazolyl)amine]quinoline.

3. A compound of the formula:

20

wherein R_1 is quinolyl and R_2 is lower alkyl or phenyl.

4. A compound according to claim 3 which is N-[(2-quinolylcarbamoyl)methyl]benzamide.
